UNITED STATES PATENT OFFICE.

JOHN J. FLANIGAN, OF CHICAGO, ILLINOIS, ASSIGNOR TO DUPLICATOR MANUFACTURING COMPANY, OF CHICAGO, ILLINOIS, A CORPORATION OF WEST VIRGINIA.

MULTIPLE-COPYING MACHINE.

1,317,486.

Specification of Letters Patent. Patented Sept. 30, 1919.

Application filed June 14, 1918. Serial No. 240,044.

To all whom it may concern:

Be it known that I, JOHN J. FLANIGAN, a citizen of the United States, residing at Chicago, in the county of Cook and State of Illinois, have invented certain new and useful Improvements in Multiple-Copying Machines, of which the following is a specification.

This invention relates to multiple copying machines or hectographs, and has reference more particularly to a rotary form of such machines wherein the printing band or apron that receives the impression from the master sheet and later transfers it to the copy sheets is stretched over the surface of an oscillating cylinder or drum, the idle portions of the printing band being wound on receiving and delivery spools journaled in the cylinder, and a fresh surface being obtained as often as required by winding up the used surface on the receiving spool and simultaneously drawing onto the surface of the cylinder a fresh surface from the delivery spool.

One difficulty that has been experienced in the practical use of such machines arises out of the excessive friction of the printing band on the surface of the cylinder, which latter usually has a surface covering of canvas or like material to afford a suitable bed or backing for the printing band, the curved form of the bed making the operation of drawing on a fresh surface difficult and likely to be attended by injury to the band itself or to the winding and unwinding mechanism. One object of the present invention, therefore, is to overcome this difficulty and provide means for facilitating the bandshifting operation.

Again, in machines of this type which employ a positively driven platen or impression roller for feeding the sheet to and impressing it on the cylindrical surface of the printing band, it has hitherto been a matter of some difficulty to accurately synchronize the rotative movement of the platen roller with that of the cylinder so as to insure a perfectly smooth and even rolling out of the sheet on the printing surface without the formation of wrinkles, creases, and similar

defects. Another object of the invention, therefore, is to improve the rotary type of copying machine in this respect also, and provide an improved driving mechanism for the platen roller that shall be positive, reliable and accurate in its action and shall always operate the platen roller in the proper predetermined speed ratio to the movement of the cylinder.

Still another object of the invention is to reduce and simplify the manual operations required to manipulate the machine, and this object I accomplish through a novel mechanism by which the platen roller and the paper-gripping roller which co-operates therewith in depositing the forward or advance end of the sheet on the printing surface are automatically separated to allow the final withdrawal of a printed sheet and the introduction of a new sheet between them by a slight additional movement of the operating handle of the cylinder itself, while the latter is idle.

Still further objects and advantages secured by the invention will be readily understood and appreciated by those skilled in the art from the following description, taken in connection with the accompanying drawings forming a part of this specification wherein I have illustrated one workable embodiment of the invention, and wherein—

Figure 1 is a rear elevation of the machine, partly broken out and in sections;

Fig. 2 is a vertical transverse section on the line 2—2 of Fig. 1;

Fig. 3 is a vertical transverse section on the line 3—3 of Fig. 1;

Fig. 4 is an end elevation, viewed from the left of Fig. 1, partly broken out;

Fig. 5 is a fragmentary view of the end opposite that shown in Fig. 4, illustrating an adjustable stop device controlling the oscillating movement of the cylinder;

Fig. 6 is a vertical transverse section on the line 6—6 of Fig. 1;

Fig. 7 is a vertical longitudinal section on the line 7—7 of Fig. 6;

Fig. 8 is a vertical longitudinal section on the irregular line 8—8 of Fig. 3,

2 Referring to the drawings, 10 designates each of a pair of vertical side frame members rigidly connected by spacing rods 11, and supported on feet 12. Journaled in 5 said side frame members is a shaft 13 on which is loosely mounted a hollow cylinder or drum comprising spiders 14 and a peripheral surface 15 that extends through slightly more than one-half of the circumference of the cylinder. Over the surface 15 is preferably stretched a covering 16 of canvas or like material that forms a suitable backing for the gelatin printing band or apron 17. The portions of this printing 10 band not engaged with the surface of the cylinder are wound on interchangeable receiving and delivery spools 18 and 19, each of said spools having duplicate ends consisting of a polygonal chuck engaging portion 20 and a round spindle or journal portion 21 (Fig. 8). Journaled in one of the cylinder spiders 14 is a winding chuck 22 for the receiving spool 18, said chuck having a ratchet 23 co-operating with a dog 24 to prevent 15 unwinding, and a shank or stem 25 adapted to receive a detachable crank 26. The spindle 21 at the other end of the receiving spool engages an open bearing 27' formed in the edge of a plate 27 secured to 20 the other spider, said bearing 27' being closed by a pivoted guard 28 that may be swung down to permit the application and removal of the spool. One end of the delivery spool 19 is engaged with a chuck 29 journaled in one of the cylinder spiders 14, said chuck 29 being provided with a ratchet 30 that is engaged by a pivoted dog 31 to hold the band taut and prevent unwinding 25 except when a fresh surface of the band is to be drawn onto the cylinder. The other end of the delivery spool 19 is journaled in an open bearing 32' formed in the edge of a plate 32 secured to the adjacent spider, said bearing 32' being closed by a pivoted guard 33 that may be swung upwardly to permit 30 the application and removal of the spool. It will be noted that the described construction of the spools, their bearings, and their winding and detent devices enables the 35 spools to be readily interchanged when necessary or desired.

As before stated, the cylinder is loose on the supporting shaft 13, but by reference to Figs. 2, 6 and 7, it will be seen that each 40 of the spiders 14 and its hub 14' carries a laterally projecting pin 34 that enters an arc-shaped slot 35 formed in a collar 36 that is keyed to the shaft 13, thereby providing for a limited relative rotary movement between the shaft and cylinder for a purpose hereinafter disclosed.

Keyed on one end of the shaft 13 is a spur gear 37 (Figs. 4 and 7) with which meshes a similar gear 38 that is removably

mounted on a fixed bearing stud 39 rigidly 65 mounted in a stiffening plate or cleat 40 secured to the outer side of the side frame member 10. Keyed on the hub 38' of the gear 38 is an operating handle 41. By swinging this handle upwardly and forwardly (to the left in Fig. 2 and to the right in Fig. 4) the shaft is rotated, and through engagement of the ends of the slots 35 with the pins 34 a simultaneous rotation 70 in the same direction is imparted to the cylinder to cause the travel of the printing bed beneath a hinged platen frame hereinafter described.

Secured on the other end of the shaft 13, with capacity for angular adjustment is a 80 radius arm 42 (Fig. 5) that co-operates in an obvious manner with a stop pin 43 carried by the adjacent side frame member 10 to limit the extent of oscillation of the cylinder.

Journaled in and between the spiders of the cylinder opposite and peripherally flush with the ends of the circumferential wall 15 of the latter are a pair of rollers 44 forming anti-friction guides for the printing 90 band 17 between the ends of said wall and the winding and delivery rolls.

Pivottally suspended from studs 45 in the hubs of the cylinder spiders is a bail-shaped yoke (Figs. 1, 2 and 3) comprising parallel 95 arms 46 that lie opposite the outer sides of the spiders and a cross-bar 47 that underlies the circumference of the cylinder parallel with the axis of the latter. The printing band 17 extends across the outer surface of the cross-bar 47, so that a portion of the band is always held by the bar out of contact with the surface of the cylinder. Each arm 46 of the yoke has a right-angle extension or branch arm 48 carrying a weight 49. The normal or idle position of this yoke is that shown in Figs. 1 and 2 and in full lines in Fig. 3. When the band is wound up on the receiving spool to bring a fresh surface into use, the pull of the band swings the yoke up to the dotted line position shown in Fig. 3 at which point one of the arms 46 strikes the upper edge of a slot 50 (Fig. 1) in the cylinder through which slot said arm passes, thereby 110 limiting the upward swing of the yoke. It will readily be seen that the effect of this yoke is to hold a considerable portion of the band out of contact with the surface of the cylinder as the winding of the band proceeds, thereby reducing friction and requiring less power to wind the band and to that extent lessening the danger of injury to the band and reducing the strain on the winding spool.

When the used portion of the band has been drawn off the bed and a fresh surface drawn thereon, and the pulling tension on the band thus relieved, the yoke 120

drops back to normal position, the braking detent 31 is applied to the delivery spool, and the machine is again ready for work.

On a rod 51 extending between the upper portions of the side frames 10 is hinged a platen frame comprising substantially a pair of side plates 52, a back plate or bar 53, and a pair of rigid arms 54 hinged on the rod 51. In the lowered position of the frames the hinge arms 54 rest on stop lugs 55 carried by the side frames 10, while similar stop lugs 56 limit the upward and backward swinging movement of the frame.

Hinged on a rod 57 mounted in and between the side plates 52 of the platen frame is a bail-shaped yoke comprising side arms 58 and a cross-bar 59; and journaled in and between the free ends of the arms 58 is a platen roller 60, one journal whereof is mounted in an open bearing 61 and is confined therein by a pivoted guard or keeper 62 (Figs. 2 and 3). Tension springs 63 anchored to the rear bar 53 of the platen frame and connected to upstanding arms 64 on the cross-bar 59 of the platen yoke tend to swing said yoke in a direction to carry the platen roller 60 down toward the bed of the cylinder; this downward swinging movement being limited by depending stop lugs 65 on the side plates 52 of the platen frame. The ends of the spindle of the platen roller extend somewhat beyond their bearings in the yoke; and to accommodate an upward swinging movement of said yoke 35 and provide clearance for said spindle ends, the side plates 52 of the platen frame are slotted as shown at 66. By reference to Fig. 8 it will be seen that one end of the spindle of the platen roll extends beyond the 40 side plate of the frame and carries a pulley 67 for a purpose hereinafter explained.

68 designates a paper gripping roll that is journaled in and between the lower ends of a pair of links 69 pivotally suspended 45 at 70 on the inner sides of the side plates 52 of the platen frame. The gripping roll 68 is pressed into contact with the platen roll 60 by springs 71 engaging the links 69, as clearly shown in Fig. 3. Stop lugs 50 72 on the side plates 52 limit the forward swing of the gripping roll when the platen roll is swung upwardly to separate said rolls for the introduction or withdrawal of a paper sheet between them. Secured to 55 the rear wall 53 of the platen frame is a widthwise adjustable pan or chute 73 that serves to guide the advance portion of the paper sheet, indicated at 74 in Fig. 3, into the platen frame and between the rollers 60 and 68 thereof. 75 designates a gage-bar (Fig. 3) of L form in cross-section that is secured to the free ends of a pair of arms 76 pivoted at 77 to the inner sides of the drum spiders 14 near the periphery of

the latter. This gage-bar normally occupies 65 the position shown in Fig. 3 opposite and flush with the forward end of the printing bed, and serves to square the forward edge of the paper sheet with reference to the bed before the sheet is gripped between the 70 rollers 60 and 68 and forced down onto the bed. Springs 78 normally hold the gage bar in working position, but permit it to be swung back out of the way when shifting the spools of the printing band. 75

The platen roller 60 is positively driven at the same surface speed as the cylinder through the following mechanism. Rotatable on the hinge rod 51 are a pair of pulleys 79 and 80 that are integral or rigidly 80 connected with each other, the former having a spirally grooved periphery and the latter a circularly grooved periphery. A cord 81 passes twice around the pulley 79 and over an end extension 15' (Fig. 1) of 85 the peripheral wall 15 of the cylinder, one end of said cord being attached to a post 82 (Fig. 2) on the outer wall of the adjacent cylinder spider 14, and the other end of the cord being attached, through a tensile spring 90 83, to a similar post 84, said spring always maintaining a taut condition of said cord. The pulley 80 is arranged in line with the platen roller pulley 67, and the two are drivingly connected by an elastic cord or 95 belt 85, preferably a coiled-wire belt as shown. In machines of the type employing a stationary flat printing bed, and a reciprocatory platen frame hinged at one end to the machine frame, and wherein the platen 100 roller is driven by a cord engaged with a spirally grooved pulley on the spindle of the platen roller, experience has shown that there is a considerable tendency of the driving cord to creep in the grooves of the pulley under the up and down swinging movements of the platen frame, and to pile up more or less at one end of the pulley. The driving mechanism of the platen roller in the present machine is entirely free from 110 this fault, and effects a uniform drive of the platen roller in accurately synchronized relation to the travel of the printing surface of the cylinder. 105

The cylinder is normally locked to the 115 shaft 13 (to which latter the operating handle is positively geared) so as to insure simultaneous movements of the drum and handle during the oscillating of the drum in both directions and without any lost motion of the handle on its return movement due to the pin and slot connection 34, 35, by a mechanism shown in Figs. 2, 6 and 7 and comprising an elbow lever pivoted at 86 to the outer wall of one of the cylinder spiders, 120 the downwardly extending arm 87 of said lever having a notch 88 that normally engages, under the influence of spring 89, a

pin or stud 90 carried by a radius arm, 91 formed on one of the collars 36 (Fig. 7) that is keyed fast on shaft 13. When, however, the cylinder has been returned to starting position, or when commencing to operate the machine, an additional movement of the handle, from the full to the dotted line position (Figs. 2 and 4) takes place in order to separate the rolls 60 and 68 for the withdrawal or introduction of the paper sheet. The pins 34 and slots 35 permit this additional movement of the handle and shaft relatively to the cylinder, but before it can take place it is necessary to withdraw lever arm 87 from pin 90. This takes place automatically, as shown in Fig. 6, through contact of the upwardly extending arm 92 of the elbow lever with an adjustable stop 93 depending from the platen frame. At the instant this takes place the rotary movement of the cylinder is arrested at the correct point by contact of a lug 94 on the spider 14 with the upper end of arm 92 of the elbow lever, which latter is then engaged with stop 93, as shown in Fig. 6.

At the conclusion of the last described operations, or at the commencement of the operation of the machine, the rollers 60 and 68 of the platen frame are opened or separated by the downward swing of handle 41 from the full to the dotted line position shown in Figs. 2 and 4 by means of an arm 95 keyed to shaft 13 (Fig. 7) and carrying at its free end a roller 96 that strikes a rigid depending arm 97 on the pivoted yoke on the platen frame that carries the platen roller 60. This swings the inner end of the yoke and the platen roller upwardly away from the gripping roller 68, as indicated by dotted lines in Fig. 6, permitting the printed sheet to be withdrawn or a new sheet to be introduced. Upon the introduction of a new sheet, with its advance edge squared against the gage-bar, the upward swing of the handle from the dotted to the full line position, Figs. 2 and 4, allows the yoke of the platen frame to descend under the pull of springs 63, gripping the paper between the rolls 60 and 68; and then carrying the advance portion of the sheet down onto the printing band. The continued upward and forward swing of the handle causes the rotation of the cylinder to the extent permitted by the stop devices 42, 43, thus rolling the sheet out on the printing bed. Thereupon the return swing of the handle returns the cylinder to starting position, during which time the sheet is peeled off the printing band by the reverse revolution of the rollers 60 and 68 (now turning in a direction to deliver the sheet). As already mentioned, a continued or additional swing of the handle in the same direction, after the cylinder has stopped, opens up the rollers of the platen frame releasing the forward end of

the printed sheet and priming the machine for the reception of the next sheet.

It is believed that the construction and manner of operation of the machine of my present invention will be readily understood by those skilled in the art from the foregoing description and illustration. While I have shown a particular mechanical embodiment of the principle of the invention, it will be manifest that the same can be to a considerable extent modified in detail without departing from its law of operation or sacrificing any of the benefits and advantages obtained thereby. I therefore do not wish to be limited to the exact mechanism shown and described, but claim all equivalents thereof which come within the spirit of the invention as defined in the appended claims.

I claim:

1. In a multiple copying machine of the type described, the combination of a rotary cylinder, a printing band overlying the peripheral surface of said cylinder, receiving and delivery spools for said band, and a bar lying lengthwise of said cylinder between the periphery of the latter and said band and holding a portion of the latter out of contact with the peripheral surface of said cylinder.

2. In a multiple copying machine of the type described, the combination of a rotary cylinder, a printing band overlying the peripheral surface of said cylinder, receiving and delivery spools for said band, and a yoke pivotally suspended from the ends of said cylinder, said yoke having a cross-bar lying lengthwise of said cylinder between the periphery of the latter and said band and holding a portion of the latter out of contact with the peripheral surface of said cylinder.

3. In a multiple copying machine of the type described, the combination of a rotary cylinder, a printing band overlying the peripheral surface of said cylinder, receiving and delivery spools for said band, a yoke pivotally suspended from the ends of said cylinder and formed with a cross-bar lying lengthwise of said cylinder between the periphery of the latter and said band, said yoke adapted to be swung upwardly partly around said cylinder as a fresh surface of the band is drawn onto the latter, and means for returning said yoke to normal position.

4. In a multiple copying machine of the type described, the combination of a rotary cylinder, a printing band overlying the peripheral surface of said cylinder, receiving and delivery spools for said band, a yoke pivotally suspended from the ends of said cylinder and formed with a cross-bar lying lengthwise of said cylinder between the periphery of the latter and said band, said yoke adapted to be swung upwardly partly around said cylinder as a fresh surface of the band is drawn onto the latter, means for lim-

- iting the extent of upward swing of said yoke, and weights on the arms of said yoke serving to return the latter to normal position.
5. In a multiple copying machine of the type described, the combination of a main frame, a printing cylinder journaled in said frame, a platen frame hinged on said main frame above said cylinder, a platen roller 10 carried by said platen frame and coöperating with said cylinder, a pulley mounted coaxially with the hinge of said platen frame, and belt connections from said pulley to said cylinder and platen roller respectively.
6. In a multiple copying machine of the type described, the combination of a main frame, a printing cylinder journaled in said frame, a platen frame hinged on said main frame above said cylinder, a platen roller 20 carried by said platen frame and coöperating with said cylinder, a pulley mounted coaxially with the hinge of said platen frame, a driving belt secured at its ends to said cylinder and passing one or more times around said pulley, and an endless driving belt connecting said pulley with said platen roller.
7. In a multiple copying machine of the type described, the combination of a main frame, a printing cylinder journaled in said frame, a platen frame hinged on said main frame above said cylinder, a platen roller 30 carried by said platen frame and coöperating with said cylinder, a pulley mounted coaxially with the hinge of said platen frame and having a spirally grooved portion and a circularly grooved portion, a driving belt passing one or more times around said spirally grooved portion and 40 thence extending in opposite directions around said cylinder and anchored at its ends to the latter, and an endless driving belt connecting the circularly grooved portion of said pulley with said platen roller.
45. 8. In a multiple copying machine of the type described, the combination of a main frame, a printing cylinder journaled in said frame, a platen frame hinged on said main frame above said cylinder, a bodily movable platen roller mounted in said platen frame 50 and coöperating with said cylinder, a pulley mounted coaxially with the hinge of said platen frame, a driving belt secured at its ends to said cylinder and passing one or 55 more times around said pulley, and an elastic endless driving belt connecting said pulley with said platen roller.
9. In a multiple copying machine of the type described, the combination of a rotatable printing cylinder, an operating handle, 60 separable driving connections between said handle and cylinder, a pair of separable paper-gripping rollers coöperating with said cylinder, a stop for arresting the turning movement of said cylinder, means for auto-
- matically separating said driving connections when the movement of the cylinder is arrested by said stop, and means actuated by said handle on a further movement thereof for separating said gripping rollers.
10. In a multiple copying machine of the type described, the combination of a rotatable printing cylinder, an operating handle, 70 separable driving connections between said handle and cylinder, a pair of separable paper-gripping rollers coöperating with said cylinder, a fixed stop for arresting the turning movement of said cylinder in one direction, an adjustable stop for arresting the turning movement of said cylinder in the other direction, means for automatically separating said driving connections when the movement of the cylinder is arrested by said fixed stop, and means actuated by said handle on a further movement thereof for separating said gripping rollers.
11. In a multiple copying machine of the type described, in combination, a main frame, a shaft journaled in said frame, a printing cylinder loose on said shaft, separable driving connections between said shaft and cylinder, a pair of separable paper-gripping rollers coöperating with said cylinder, a stop for arresting the turning movement of said cylinder, means for automatically disconnecting said shaft from said cylinder when the movement of the latter is arrested by said stop, and means actuated by said shaft on a further turning movement thereof for separating said gripping rollers.
12. In a multiple copying machine of the type described, the combination of a main frame, a printing cylinder rotatably mounted therein, an operating handle for said cylinder, a platen frame mounted on said main frame, a pivoted yoke carrying a platen roller in said platen frame, and means for swinging said yoke from said handle during the final part of the movement of said handle in one direction.
13. In a multiple copying machine of the type described, the combination of a main frame, a printing cylinder rotatably mounted therein, a stop for limiting the turning movement of said cylinder, an operating handle, 105 connections between said handle and cylinder permitting an excess movement of the former after the latter has been arrested by said stop, a pivoted yoke carrying a platen roller in said platen frame, and means actuated by said handle during its excess movement for swinging said yoke.
14. In a multiple copying machine of the type described, in combination, a hollow rotary cylinder having a parti-cylindrical 115 surface forming a printing bed, a printing band overlying said bed, interchangeable spools for the idle portions of said band within said cylinder, bearings and winding devices for said spools mounted on the end 120

walls of said cylinder, and a pivoted gage-bar disposed opposite one end of said printing bed.

15. In a multiple copying machine of the type described, in combination, a hollow rotary cylinder having a parti-cylindrical surface forming a printing bed, a printing band overlying said bed, interchangeable spools for the idle portions of said band

within said cylinder, bearings and winding devices for said spools mounted on the end walls of said cylinder, a pair of arms pivoted to the end walls of said cylinder, and a gage-bar mounted on the free ends of said arms and lying opposite one end of said printing bed.

JOHN J. FLANIGAN.
